UNITED STATES PATENT OFFICE.

ALFRED KOHN, OF CHICAGO, ILLINOIS, ASSIGNOR TO GLASER, KOHN & CO., OF SAME PLACE.

DESIGN FOR A BOTTLE.

SPECIFICATION forming part of Design No. 18,572, dated August 28, 1888.

Application filed July 18, 1888. Serial No. 280,337. Term of patent 3½ years.

To all whom it may concern:

Be it known that I, ALFRED KOHN, a citizen of the United States, residing at Chicago, in the county of Cook and State of Illinois, have invented and produced a new and original Design for Bottles; and I do declare the following to be a full, clear, and exact description of the same, reference being had to the accompanying drawings, forming a part thereof.

10 The design is illustrated in the accompanying drawings, in which—

Figure 1 is a side view of a bottle embodying my design. Fig. 2 is a top view of the lid or cover.

15 The main body of the bottle flares upwardly and outward from the base *a* to the line *b*, and from thence the sides of the bottle are gradually contracted or tapered upwardly and inwardly to the line *c*, from which point the 20 sides are carried up to form the neck *d*, and then flared outwardly to form the mouth *e*, said mouth being enlarged or provided with a ledge to receive the cap or cover *f*. The lower portion of the bottle is provided with

flutes or corrugations *g*, which extend up to 25 and merge into a banding of smaller flutings, *h*, arranged in the form of basket or wicker work, which extends from the top of the flutes *g* to the lower end of the neck of the bottle. The top or cover of the bottle has a central 30 raised portion, *i*, around which are arranged a series of flutings, *k*, in imitation of basket or wicker work.

What I claim, and desire to secure by Letters Patent, is—

35 The design for bottles, consisting of a bottle round in cross-section and tapering from the bulge at the neck to the bottom thereof, the lower portion having the plain flutings *g* and the upper portion the flutings *h*, arranged 40 in the form of basket or wicker work, substantially as shown and described.

In testimony whereof I affix my signature in presence of two witnesses.

ALFRED KOHN.
